UNITED STATES PATENT OFFICE.

CLARENCE J. ALDEN, OF PAINESVILLE, OHIO, ASSIGNOR TO THE PAINESVILLE METALIC BINDING COMPANY, OF PAINESVILLE, OHIO, A COPARTNERSHIP COMPOSED OF CLARENCE J. ALDEN AND PERCY K. SMITH.

CURTAIN SUPPORT.

Application filed July 19, 1922. Serial No. 575,992.

To all whom it may concern:

Be it known that I, CLARENCE J. ALDEN, a citizen of the United States, residing at Painesville, in the county of Lake and State 5 of Ohio, have invented certain new and useful Improvements in Curtain Supports; and I do hereby declare the following to be a full, clear, and exact description of the invention, such as will enable others skilled in 10 the art to which it appertains to make and use the same.

This invention relates to a combined curtain rod and bracket adapted to be easily and quickly connected or disconnected.

15 The objects are to simplify and cheapen the construction of curtain rods and brackets, to render the rod readily attachable to and detachable from the bracket, and to produce a light and strong fixture.

20 With these and other objects in view, the invention consists in the combination and details of structure more fully set forth in the ensuing description, illustrated in the accompanying drawing and defined in the 25 appended claims.

In the accompanying drawings:—

Figure 1 is a perspective view, seen from above, of a curtain rod and pair of brackets connected to a window frame.

30 Fig. 2 is a plan of one bracket and the end of a curtain rod attached thereto, viewed from above.

Fig. 3 is an elevation of a bracket, with the end of a curtain rod shown engaging the 35 bracket, the curtain rod having been severed adjacent the end.

Fig. 4 is a plan view on a greatly enlarged scale of the curtain rod adapted to engage the bracket.

40 Fig. 5 is a perspective illustrating a modification in the structure of a curtain rod end;

Fig. 6 is a front elevation of a modified bracket; and

Fig. 7 is a view looking down upon the 45 bracket shown in Fig. 6.

In the drawings, F is a conventional illustration of the upper portion of a window frame. Secured at opposite sides of the upper portion of the window frame are brackets 1 and 1^a, respectively. These brackets are offset intermediate their ends to provide securing lugs 2, through holes 3 of which securing means may be passed. The offset or

bulge 4 is provided with one or more vertical narrow slots 5 for the reception of the 55 curtain rod now to be described.

The curtain rod is indicated at 6 and is preferably adjustable in length as is customary. Each end of the rod is bent at right angles as at 7 as is also customary. 60 The curtain rod is preferably of flat material having curled over longitudinal edges. To provide for interlocking engagement with the bracket, the flat portion 7 is constructed to provide a web 11 which is adapted to be received within the narrow slot 5 in the bracket. At the outer extremity of the web is a lateral stop or lug 9 which together with a second lug or stop 10 formed as part of the portion 7 of the curtain rod, holds 70 the web in place in the bracket. In the form of the invention shown in Figs. 2, 3, and 4 the stop or lug 10 constitutes a laterally bent part of the portion 7, the web 10 a rearwardly bent part, and the lug 9 a laterally bent part. The web is preferably notched at its bottom, by which construction the lower ends of the stop members 9 and 10 extend slightly below the bottom 75 of the slot 5 when the rod is engaged therewith and afford additional security in the connection.

In bending the above described construction it will be apparent that the curled edges of the curtain rod may be forced inward at the bend as indicated in Fig. 1. The goose-neck or U-shaped extremity constituted by the said web and stops may be formed on the rod by bending or die swaging, and the metal at the edges of the portion 11 that engages in the slot of the bracket may be removed by the same or by a separate operation, as will be apparent to those skilled in the art of shaping metals. It will thus be seen that a curtain rod of 90 light structure may be produced very cheaply, and that by reason of the form shown, this rod will be of great strength in comparison with its weight and may be instantly attached to or detached from the 95 bracket.

A modified curtain-rod end is shown in Fig. 5. In this form the curled edges at the ends are flattened into flanges 12 which extend at right angles from the body and 100 cross notches 13 are cut or otherwise formed 105

in said flanges to constitute a bracket engaging groove. Shoulders or stops 14 and 15 are adapted to be engaged behind and in front of the bracket body, when the cross 5 grooved end of the rod is seated in the slot 5 of the bracket. In this construction the web which enters the slot in the bracket is constituted by the upright portion of the curtain rod as will be readily understood.

10 A modified form of bracket 21 having the securing flanges at opposite ends instead of at opposite sides is illustrated in Figs. 6 and 7. The flanges 22 have holes 23 for the reception of nails or screws whereby the bracket may be secured to a window frame. The offset body 24 is convexed in a vertical 15 instead of a horizontal plane (when in normal position on a window frame). A slot 25 is adapted to receive the transversely 20 grooved end of a curtain rod, and the upper portion of said body 24 where it bends at 24^a to form the upper flange 22 is cut away to admit passage of the extremity of the

curtain rod when being engaged with the bracket.

Having described my invention, what I claim and desire to secure by Letters Patent of the United States, is:—

1. The combination with a bracket, of a curtain rod having a flat extension, said extension having its terminal bent laterally, rearwardly and laterally to provide a web between said lateral portions, said bracket having a narrow vertical slot for the reception of said web.

2. The combination with a bracket, of a curtain rod having a flat extension, a portion of said extension constituting a vertically disposed web, shoulders on said extension at either side of said web, said bracket having a narrow vertical slot for the reception of said web, the web being retained in place in said slot by means of said shoulders.

In testimony whereof I affix my signature.

CLARENCE J. ALDEN.
